R. SUCZEK.

CONDENSING APPARATUS.

APPLICATION FILED JAN. 17, 1919.

1,373,463.

Patented Apr. 5, 1921.

UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

CONDENSING APPARATUS.

1,373,463.

Specification of Letters Patent. Patented Apr. 5, 1921.

Application filed January 17, 1919. Serial No. 271,622.

To all whom it may concern:

Be it known that I, ROBERT SUCZEK, a citizen of the Czechoslovak Republic, residing in the city and county of Philadelphia, State 5 of Pennsylvania, have invented certain new and useful Improvements in Condensing Apparatus, of which the following is a specification.

My invention relates to apparatus for condensing fluid, as steam, and removing uncon- 10 densable fluid, as air, which may be contained in or in association with the condensable fluid before or after condensation.

My invention resides in condensing appa- 15 ratus of any suitable type, more particularly a surface condenser, with which is associated air removing apparatus comprising an ejector which discharges through a passage or passages within which the condensable fluid 20 from the mixture of the ejector is condensed and the uncondensed fluid cooled by extraction of heat from the walls of said passage or passages by cooling medium, as water, which is preferably that which thereafter 25 effects condensation of steam in the condenser. With such apparatus may be associated a pump for further raising the pressure of the uncondensed fluid from the ejector, said pump being of any suitable type, 30 and is preferably another ejector.

My invention resides also in the apparatus hereinafter described.

For an illustration of one the various forms my invention may take, and for an 35 illustration of a mode of practising my method, reference is to be had to the accompany- 40 pany drawing, in which:

Figure 1 is a side elevational view of an embodiment of my invention comprising a 45 surface condenser with which is associated multiple stage ejector apparatus with inter- 50 stage condensing structure.

Fig. 2 is partly an elevation and partly a section, taken on the line 2-2 of Fig. 1.

Fig. 3 is a fragmentary elevational view, 45 partly in section, on the line 3-3 of Fig. 2.

Referring to the drawing, C is the shell of a surface condenser comprising, in the example illustrated, two banks of cooling 50 water conducting tubes *a* and *b*, extending longitudinally thereof and terminating at

one end in the cooling water box A and at the other end in the cooling water box B. The grouping of the tubes *a* and *b* is with respect to the partition or diaphragm *c* in 55 the water box A, to which cooling water is admitted through the intake *d*. The water flows through the group of tubes *b* to the water box B, thence forwardly again through the group of tubes *a* to the upper 60 compartment of the water box A and thence outwardly through the cooling water outlet *e*. The fluid to be condensed, as steam from steam turbines, engines or any other source, enters the condenser at D into the dome F 65 above the upper tubes *a*, flows around and between said tubes into the space between and around the tubes *b* of the lower group, and in so passing is condensed, the water of condensation or condensate being received in the 70 hot well G, from which it is withdrawn through the pipe *f* by a suitable pump.

The condenser structure as described is one well known in the art, and is given merely as an example of many structures 75 which may be used in a combination embodying my invention.

In this connection it will be understood that my invention is not limited, except where so specified in the claims, to a surface 80 condenser, inasmuch as some features of my invention are applicable with condensers of other types, as for example, jet condensers.

Communicating with the vacuum space within the condenser is the pipe *g* for conducting air or uncondensable vapors or gases to the ejectors E and E¹, whose suction chambers are in communication with the pipe *g* through the valves *h* and *h*¹, respectively. The ejectors E and E¹ are of 90 any suitable type, preferably and here indicated as of the tubular type, though it will be understood that both or either may be of the radial flow type producing disk-shaped jet receiving into a surrounding diffuser. 95 Motive fluid, as live or exhaust steam, is furnished the ejectors E and E¹ through the valves *i* and *i*¹, pipes *j* and *j*¹, and valves *k* and *k*¹.

Secured to a flange 1 on the water box A, 100 preferably adjacent the cooling water inlet passage *d*, is a tube sheet or plate *m* which

is a wall common to the water box A and the chambers or compartments n , o , n^1 and o^1 of a chest or box H having the horizontal partition p and the vertical partition p^1 dividing the interior of the chest H into the aforementioned four compartments. Connecting the compartments n and o is a plurality of tubes q extending forwardly into the water box A adjacent the cooling water inlet D and extending backwardly to the compartment o . Similarly, a group of tubes q^1 afford communication between the compartments n^1 and o^1 , and are disposed beside the tubes q preferably in like position with respect to the water box A and the inlet d . The ejectors E and E^1 discharge, respectively, through the pipes or passages r and r^1 into the compartments n and n^1 . From the compartments o and o^1 extend pipes or passages s and s^1 to the suctions of pumps P and P^1 , respectively, which may be of any suitable type for compressing elastic fluid, and may be reciprocating, rotary, entrainment, wet or dry or hydraulic air pumps, or any other suitable type of pump; but preferably the pumps P and P^1 are steam actuated ejectors of any suitable type, and may be and preferably are radial flow ejectors producing disk-shaped jets received into surrounding annular diffusers. In fact, the ejectors of each pair, as E and P , may be, respectively, tubular and radial flow ejectors such as disclosed, for example, in Letters Patent of the United States No. 1,282,595, the ejectors P, P^1 receiving their motive fluid through the aforementioned valves i and i^1 . The ejectors P and P^1 have their discharge outlets at t and t^1 , respectively.

Communicating respectively with the bottoms of the compartments o and o^1 are the condensate draw-off pipes u and u^1 , controlled by valves v , v^1 and delivering into the pipe w , which delivers into the hot well G or is led to any other suitable destination.

The operation is as follows:

Steam entering at D is condensed in coming into contact with the cooling water conducting tubes a and b , the condensate passing to the hot well G from which it is withdrawn through pipe f . Uncondensable vapors or air within the condenser are removed, to maintain vacuum therein, by the ejector E whose discharge is passed through the tubes q , wherein the motive fluid or steam for the ejector E or other condensable vapor is condensed, the condensate and air being delivered into the chamber o , and the condensate drawn off through the pipe u^1 while the air is delivered to the second stage pump or ejector and further raised in pressure.

The condensation in the tubes q is effected by the cooling water entering at d , before such water has entered the condenser tubes, and therefore before it has effected any con-

densation and before it has risen in temperature. This will effect very thorough condensation in the tubes q^1 and effect a large fall in temperature of the air and uncondensable vapor, which is accordingly increased in density and more easily operated upon by the second stage pump or ejector P.

The operation is also the same for the other ejector E^1 and its associated pump or ejector P^1 , with their intermediately connected tubes q^1 .

Communication with either ejector E or E^1 with the interior of the condenser may be discontinued by closing the associated valve h or h^1 . When this is done the other ejector may continue in operation, as when the amount of air to be withdrawn from the condenser is so small as to be readily taken care of by one ejector or one pair of ejectors. Or in case of trouble with either pair, that pair may be isolated by closing its associated valve h or h^1 and preferably also by closing the associated valve v or v^1 . By this structure, involving interstage condenser tubes for each pair of ejectors, each pair is separate and distinct from the other and may be isolated with advantage, as distinguished from the case where the interstage ejector has a condensing chamber common to both pairs of ejectors.

Certain broad subject matter germane to this application and to my co-pending application Ser. No. 271,621, filed January 17, 1919, is not herein claimed, but is claimed in said co-pending application.

What I claim is:

1. The combination with a condenser having a box or distributing chamber as a part thereof receiving the cooling medium before its operation upon the fluid to be condensed, of an ejector, and a condenser receiving the discharge from said ejector having its heat transfer structure disposed within said box or chamber.

2. The combination with a surface condenser comprising cooling medium conducting tubes, of a cooling medium box or chamber communicating with said tubes, an ejector, and a surface condenser receiving the discharge from said ejector and having its heat transfer structure disposed in said box or chamber.

3. The combination with a plurality of ejectors, of a chest divided into compartments, a pair of compartments for each ejector, tubes connecting the compartments of a pair and conducting from one of them to the other the discharge from the ejector, and means for subjecting the tubes associated with the said ejectors to the same cooling medium.

4. The combination with a condenser, of means for supplying cooling medium thereto, a plurality of ejectors arranged in parallel, a group of tubes for each ejector re-

ceiving the discharge therefrom, and means for subjecting the groups of tubes to said cooling medium.

5. The combination with a condenser, of means for supplying cooling medium thereto, a plurality of ejectors, a group of tubes for each ejector receiving the discharge therefrom, and means for subjecting the groups of tubes to said cooling medium before it reaches heat transfer relation with the condensable fluid in said condenser.

6. The combination with a plurality of ejectors, of a chest divided into compartments, a pair of compartments for each 15 ejector, tubes connecting the compartments of a pair and conducting from one of them to the other the discharge from the ejector, means for subjecting the tubes associated with the said ejectors to cooling medium 20 from the same source, and a pump further increasing the pressure of the uncondensed fluid from each of said ejectors.

7. The combination with a plurality of ejectors, of a chest divided into compartments, a pair of compartments for each 25 ejector, tubes connecting the compartments of a pair and conducting from one of them to the other the discharge from the ejector, means for subjecting the tubes associated 30 with the said ejectors to cooling medium from the same source, and an ejector for further raising the pressure of the uncondensed fluid from each of said ejectors.

8. The combination with a condenser, of means for supplying cooling medium thereto, a plurality of ejectors, a group of tubes for each ejector receiving the discharge 35 therefrom, means for subjecting the groups of tubes to said cooling medium, and a pump further increasing the pressure of the uncondensed fluid from each of said ejectors.

9. The combination with a condenser, of means for supplying cooling medium thereto, a plurality of ejectors arranged in parallel, a group of tubes for each ejector receiving the discharge therefrom, means for subjecting the groups of tubes to said cooling medium, and an ejector for further raising the pressure of the uncondensed fluid from 50 each of said ejectors.

10. The combination with a condenser, of means for supplying cooling medium thereto, a plurality of ejectors, an independent group of tubes for each ejector receiving the 55 discharge therefrom, means for subjecting the groups of tubes to said cooling medium before it reaches heat transfer relation with the condensable fluid in said condenser, and a pump further increasing the pressure of the uncondensed fluid from each of said 60 ejectors.

11. The combination with a condenser, of means for supplying cooling medium thereto, a plurality of ejectors, a group of tubes 65 for each ejector receiving the discharge

therefrom, means for subjecting the groups of tubes to said cooling medium before it reaches heat transfer relation with the condensable fluid in said condenser, and an ejector further raising the pressure of the uncondensed fluid from each of said ejectors.

12. The combination with a condenser, of means for supplying cooling medium thereto, a plurality of ejectors, a group of tubes for each ejector receiving the discharge 75 therefrom, means for subjecting the groups of tubes to said cooling medium, and a valve for isolating the suction chamber of each of said ejectors from the interior of said condenser.

13. The combination with a condenser, of means for supplying cooling medium thereto, a plurality of ejectors, a group of tubes for each ejector receiving the discharge 80 therefrom, means for subjecting the groups of tubes to said cooling medium before it reaches heat transfer relation with the condensable fluid in said condenser, and a valve for isolating the suction chamber of each of said ejectors from the interior of said condenser.

14. The combination with a condenser having a hot well, of means for supplying cooling medium thereto, an ejector, a second condenser receiving the discharge from said 95 ejector, means for subjecting said second condenser to said cooling medium before it absorbs heat from the condensable fluid within the first condenser, and means for delivering condensate from said second condenser to said hot well.

15. The combination with a surface condenser, of an ejector and a condenser receiving the discharge therefrom disposed in said surface condenser and cooled by the cooling 105 medium thereof.

16. The combination with a surface condenser, of an ejector, and a condenser receiving the discharge therefrom disposed in said surface condenser and cooled by the cooling 110 medium thereof before it reaches heat transfer relation with the condensable fluid therein.

17. The combination with a surface condenser, of an ejector mounted thereon, and a condenser receiving the discharge therefrom disposed in said surface condenser and cooled by the cooling 115 medium thereof.

18. The combination with a surface condenser, of a plurality of ejectors mounted 120 upon said condenser, and a second condenser interstage with said ejectors disposed in said surface condenser and cooled by the cooling medium thereof.

19. The combination with a condenser, of a plurality of ejectors having their suction chambers connected therewith, means for raising the pressure of elastic fluid removed from said condenser by said ejectors, condenser structure intervening between said 125 130

means and each of said ejectors for condensing the condensable component of the discharge from said ejectors, said condenser structure comprising an independent heat transfer structure for each of said ejectors, means for subjecting said heat transfer structures to cooling medium, and means for

isolating either of said suction chambers from said first named condenser.

In testimony whereof I have hereunto affixed my signature this 16th day of January, 1919.

ROBERT SUCZEK.
